UNITED STATES PATENT OFFICE.

GURDON PENDLETON, OF NORTH ATTLEBORO, MASSACHUSETTS.

METAL-CUTTING TOOL.

1,356,882.

Specification of Letters Patent. Patented Oct. 26, 1920.

Application filed February 27, 1920. Serial No. 361,881.

To all whom it may concern:

Be it known that I, GURDON PENDLETON, a citizen of the United States, residing at North Attleboro, in the county of Bristol 5 and State of Massachusetts, have invented new and useful Improvements in Metal-Cutting Tools, of which the following is a specification.

This invention relates to improvements in 10 tools for cutting metal and more particularly to the class of tools known as band iron cutters.

The object of the invention is to provide 15 a powerful hand tool for removing bands of metal from around bales of cotton, packing cases and the like where the said bands very closely engage the bales or cases and because of said close engagement are very difficult to sever.

20 It is an object therefore, of the invention to so construct and arrange the cutting instrumentalities of the tool and connect the same to the operating handles that with the initial movement of the handles the movable 25 members of the cutting instrumentalities will first be forced beneath the edges of the band of metal and if there is a solid backing as, for example, in packing cases or boxes, said band will be forced away from the case 30 as the handles are forced together, a curved end portion of the movable cutting members constituting a fulcrum to pry said band away from said case or in the event that the backing yields, as would be the case in a 35 bale of cotton, the said movable members will be forced beneath the band, the said band in each instance being then forced against a stationary cutter with which the movable members finally coöperate to sever 40 the band.

It is also an object of the invention to increase the power applied by the handles to the movable cutting members by employing 45 a triple toggle mechanism in connecting said handles and the movable cutting members together.

The invention consists in the combination and arrangement of parts set forth in the following specification and particularly 50 pointed out in the claims thereof.

Referring to the drawings:

Figure 1 represents a plan view of a metal cutting tool embodying my invention, the cover plate thereof being partly broken away, the tool being illustrated in its open

position and in engagement with a bale of cotton or the like.

Fig. 2 represents an end elevation of the metal cutting tool.

Fig. 3 is a plan view similar to Fig. 1 but 60 illustrating the tool in its closed position, and in engagement with the side of a packing case.

Fig. 4 is a side elevation with the various parts occupying the same positions as illustrated in Fig. 3. 65

Like numerals refer to like parts throughout the several views of the drawings.

In the drawings: 1 represents a frame to which is secured by means of bolts 2 a reversible stationary cutter 3 provided with a pair of concave cutting edges 4 and 5 upon opposite ends thereof. Pivoted upon the bolts 2 with their sides contacting with the side of the stationary cutter 3 are a pair of 70 movable cutting members 6. The movable cutting members 6 each have a V-shaped notch 7 in their opposite adjacent edges, one side of said V-shaped notch constituting a cutting edge 8. The movable cutting 75 members 6 are also provided with a curved outer end 9 which intersects the cutting edge 8 and forms a pointed extremity 10. When the movable cutting members are rocked upon their pivots 2, the pointed extremities 10 are forced between the under surface of a sheet metal band A and the outer surface of a bale B or packing case C around which said band may extend. When a metal band is being removed from a 80 case C which provides a solid backing, as illustrated in Fig. 3, the curved edge 9 constitutes a fulcrum and as the movable cutting members are rocked upon their pivots 2 they will also rock upon the fulcrum and force the band A away from the case. 85

The movable cutting members 6 are each rocked in unison upon their pivots 2 by a link 11, one end of which is pivotally attached to said movable cutting members by a stud 12 and the other end is pivotally attached by a stud 13 to a slide 14. The links 11 and slide 14 coöperate with each other to form a toggle mechanism 15. The slide 14 is 100 adapted to reciprocate in a groove 16 provided in the frame 1, motion being imparted thereto by means of a pair of bell-crank levers 17 which are pivotally attached to the frame 1 by bolts 18. The bell-crank 105

levers 17 are formed with a long arm 19 which constitutes a handle therefor, and a short arm 20. The short arm 20 of each lever 17 is connected by a link 21 attached thereto at 22 to the slide 14 to which it is attached by a stud 23. The short arm 20 of each bell-crank lever 17 coöperates with the link 21 attached thereto to form a toggle mechanism 24. The movement of the slide 14 in each direction is limited by plates 25 and 26 which are located within the groove 16 at each end thereof, the opposite ends of the slide 14 abutting thereagainst.

A cover plate 27 is located above the movable cutting members 6, links 11 and 21 and ends 20 of the bell-crank levers and is held in place by the bolts 2 and 18. The cover plate 27, not only acts to stabilize each of the toggle mechanisms and hold the slide 14 in the bottom of the groove 16 but the forward edge constitutes a rest 28 against which the metal band A is supported upon the opposite side laterally of the movable cutting members 6 from the stationary cutter 3, while said band is being severed as illustrated in Fig. 4.

The operation of my improved metal cutting tool is as follows:

When it is desired to sever a metal band in order that the same may be removed from around a bale of cotton or the like to which it is very closely attached, the handles 19 of the tool are grasped and separated, thereby simultaneously separating the outer ends of the movable cutting members 6. The tool is then placed against the bale as illustrated in Fig. 1 and the handles 19 moved together, enough pressure being simultaneously placed longitudinally of the tool to cause the points 10 of the movable cutting members to pass behind the band A as said points approach each other. As the handles 19 are forced together, the two toggle mechanisms 24 simultaneously force the slide 14 longitudinally of the slot 16 toward the outer end of the tool thereby causing the toggle mechanism 15 to force the inner end of each of the movable cutting members 6 outwardly. This movement will simultaneously force each of the pointed ends 10 beneath the metal band A and then force said band against the stationary cutter 3. A further movement of the handles 19 toward each other will result in severing the band. The cutting edges 8 of each movable cutting member 6 coöperate with the stationary cutter 3 to sever said band from the opposite edges thereof inwardly. The stationary cutter 3 has a concave cutting edge and because of this fact, less power is required to sever the metal and the portion of the metal adjacent to the severed end is not as badly distorted as is the case where the cutting edge is straight. Where the tool is used to sever a metal band which is

extending around a packing case the points 10 are forced beneath the opposite edges of the band and as the movable cutting members 6 are rocked upon their pivots 2 the curved edge portion 9 of said members will engage the packing case as illustrated in Fig. 3 and act as a fulcrum to pry the metal band away from the case as the points are forced together. During the severing operation, the rest 28 will engage the metal band and act as a support for said band upon the opposite side of the movable cutting member 6 from the stationary cutter 3.

When the cutting edge 4 of the stationary cutter becomes dull or has been ground away too far to be of further use the said stationary cutter may be reversed and the cutting edge 5 utilized. The under surface of the cover plate 27 contacts with the upper surface of the links 11 and 21 and acts to stabilize the toggle mechanisms of which said links constitute a part, and tends to hold the slide 14 in its proper position in the groove 16. The arrangement of the toggle mechanisms greatly increases the power applied by the handles to force the movable cutting members.

Having thus described my invention what I claim and desire by Letters Patent to secure is:

1. A metal cutting tool of the character described having, in combination, a stationary cutter, a plurality of movable cutting members each embodying therein a pointed outer extremity, and means to force said pointed extremities between a band of sheet material and a bale or the like around which said band extends and thereafter force said band into cutting engagement with said stationary cutter.

2. A metal cutting tool of the character described having, in combination, a stationary cutter, a plurality of movable cutting members each embodying therein a pointed outer extremity, and means to simultaneously force said pointed extremities beneath the opposite edges of a band of sheet material and between said band and a bale or the like around which said band extends and thereafter force said band into cutting engagement with said stationary cutter.

3. A metal cutting tool of the character described having, in combination, a reversible stationary cutter provided with a concave cutting edge, a plurality of movable cutting members each embodying therein a pointed outer extremity, and means to simultaneously force said pointed extremities beneath the opposite edges of a band of sheet material and between said band and a case or the like around which said band extends and thereby simultaneously force said band away from said case and into cutting engagement with said stationary cutter.

4. A metal cutting tool of the character

described having, in combination, a stationary cutter, a plurality of movable cutting members each embodying therein a pointed outer extremity and a portion adjacent thereto constituting a fulcrum, and means to simultaneously force said pointed extremities between a band of sheet material and a case or the like around which said band extends, and rock said movable cutting member upon said fulcrum and thereby force said band away from said case and into cutting engagement with said stationary cutter.

5. A metal cutting tool of the character described having, in combination, a reversible stationary cutter, a plurality of movable cutting members each embodying therein a wedge-shaped outer extremity, and means to force said wedge-shaped extremity between a band of sheet metal and a bale or the like around which said band extends and thereafter force said band into cutting engagement with said stationary cutter.

6. A metal cutting tool of the character described having, in combination, a stationary cutter, a plurality of movable cutting members each embodying therein a wedge-shaped outer extremity, and means to force said wedge-shaped extremity between a band of sheet metal and a bale or the like around which said band extends and thereafter force said band into cutting engagement with said stationary cutter, and sever said band from the opposite edges thereof inwardly.

7. A metal cutting tool of the character described having, in combination, a stationary cutter provided with a concave cutting edge, a pair of movable cutting members each provided with a cutting edge, and means to force each of said movable cutting members into engagement with a band of sheet material and force said band into cutting engagement with said stationary cutter and thereby sever said band from the opposite edges thereof inwardly.

8. A metal cutting tool of the character described, having, in combination, a stationary cutter, a plurality of movable cutting members each embodying therein a wedge-shaped outer extremity, and means to force said wedge-shaped extremity between a band of sheet metal and a bale or the like around which said band extends and thereafter force said band into cutting engagement with said stationary cutter to sever said band from the opposite edges thereof inwardly, and means located upon the opposite side laterally of said movable cutting member from said stationary cutter adapted to engage said band during the severing operation and provide a rest therefor.

9. A metal cutting tool of the character described having, in combination, a stationary cutter, a plurality of movable cutting

members, and means to force said movable cutting members into coöperating relation with said stationary cutter to sever material inserted therebetween, said means embodying therein a triple toggle movement.

10. A metal cutting tool of the character described having, in combination, a stationary cutter, a plurality of movable cutting members, a pair of operating handles, a toggle mechanism adapted to simultaneously move each of said movable cutting members into coöperating relation with said stationary cutter and sever material inserted therebetween, and a pair of other toggle mechanisms adapted to operate said first mentioned toggle mechanism, each of said last mentioned toggle mechanisms being connected to and operated by one of said handles.

11. A metal cutting tool of the character described having, in combination, a frame, a stationary cutter attached to said frame, a plurality of movable cutting members pivotally mounted upon said frame each provided with a cutting edge, and means to force each of said movable cutting members into engagement with a band of sheet material and force said band into cutting engagement with said stationary cutter and thereby sever said band from the opposite edges thereof inwardly.

12. A metal cutting tool of the character described having, in combination, a frame, a stationary cutter attached to said frame, a plurality of movable cutting members pivotally mounted upon said frame, each embodying therein a pointed outer extremity and a portion adjacent thereto constituting a fulcrum, a pair of bell-crank levers, a toggle mechanism adapted to simultaneously move each of said movable cutting members into coöperating relation with said stationary cutter to sever material inserted therebetween, and means to connect said toggle mechanism with each of said bell-crank levers.

13. A metal cutting tool of the character described having, in combination, a frame, a stationary cutter attached to said frame, a plurality of movable cutting members pivotally mounted upon said frame, each embodying therein a pointed outer extremity and a portion adjacent thereto constituting a fulcrum, a pair of bell-crank levers, a toggle mechanism adapted to simultaneously move each of said movable cutting members into coöperating relation with said stationary cutter to sever material inserted therebetween, said toggle mechanism embodying therein a slide and a pair of links connecting said slide with said movable cutting members, and a second pair of links connecting said toggle with said bell-crank levers.

14. A metal cutting tool of the character

- described having, in combination, a frame, a stationary cutter attached to said frame, a plurality of movable cutting members pivotally mounted upon said frame, each embodying therein a pointed outer extremity and a portion adjacent thereto constituting a fulcrum, a pair of bell-crank levers, a toggle mechanism adapted to simultaneously move each of said movable cutting members into coöperating relation with said stationary cutter to sever material inserted therebetween, said toggle mechanism embodying therein a slide and a pair of links connecting said slide with said movable cutting members, and a second pair of links connecting said toggle mechanism with said bell-crank levers, each of said last mentioned links coöperating with one of said bell-crank levers to form other toggle mechanisms.
15. A metal cutting tool of the character described having, in combination, a frame, a reversible stationary cutter provided with a plurality of independent concave cutting edges, a plurality of movable cutting members mounted upon said frame, each em-

bodying therein a wedge-shaped outer extremity and a portion adjacent thereto constituting a fulcrum, a pair of bell-crank levers, a toggle mechanism adapted to simultaneously move each of the said movable cutting members into coöperating relation with said stationary cutter to sever metal inserted therebetween, said toggle mechanism embodying therein a slide and 30 a pair of links connecting said slide with said movable cutting members, a second pair of links connecting said toggle mechanism with said bell-crank levers, each of said last mentioned links coöperating with one of 35 said bell-crank levers to form other toggle mechanisms, and a plate against which said band is adapted to rest upon the opposite side laterally of said movable cutting members from said stationary cutter.

40 In testimony whereof I have hereunto set my hand in presence of two subscribing witnesses.
